(57) CLAIM

The ornamental design for a combined gift card holder box with spinner, as shown and described.

DESCRIPTION

FIG. 1 is a perspective view of the combined gift card holder box with spinner of the present invention, in an open position.

FIG. 2 is a left side view of the combined gift card holder box with spinner of FIG. 1, the right side view being a mirror image thereof.

FIG. 3 is a front view of the combined gift card holder box spinner of FIG. 1.

FIG. 4 is a rear view of the combined gift card holder box with spinner of FIG. 1.

FIG. 5 is a top down view of the combined gift card holder box with spinner of FIG. 1.

FIG. 6 is a bottom up view of the combined gift card holder box with spinner of FIG. 1.

FIG. 7 is a perspective view of the combined gift card holder box with spinner of FIG. 1, in a closed position; and,

FIG. 8 is a left side view of the combined gift card holder box with spinner of FIG. 7, the right side view being a mirror image thereof.

In the drawings, the dash-dash broken lines are for the purpose of illustrating portions of the combined gift card holder box with spinner that form no part of the claimed design.

1 Claim, 4 Drawing Sheets
